ISAAC C. LIGHTFOOT, OF SAN BERNARDINO, CALIFORNIA

DRY CONCENTRATOR

Application filed September 28, 1931. Serial No. 565,434.

This invention relates to improvements in dry concentrators and has reference more particularly to an improved apparatus and method for separating fine gold particles from ground quartz, gravel or other nonmetallic material.

It is well known that there exists in many parts of this country, and also in many other countries, great quantities of gravel and sand with which is mixed gold in the form of fine powder or flakes. These deposits are usually found in places where the rainfall is very limited and where water is very scarce and therefore the separation of the gold cannot be effected by any method that requires a considerable quantity of water.

It is one of the objects of this invention to produce an apparatus that shall be so constructed that by means of it gold can be separated from any dry powdered material and this apparatus is therefore especially well adapted for desert places where water is unavailable.

It has been found from experience that if dry ground ore or gravel is first carefully screened so as to remove all particles above a certain size and then deposited on an inclined chute that is vibrated by mechanical means in such a way as to cause a layer of this material to flow downwardly, and then pass a strong current of air upwardly through it, the constant agitation produced by the mechanical vibration of the chute and by the current of air permits the gold particles to gravitate to the bottom of the chute where they can be collected.

This invention briefly described consists of an apparatus having a supporting framework comprising, in part, a box-like receptacle open at the top and having its top edges inclined towards one end, a chute is located above this receptacle and has its lower end pivotally connected with the lower end of the receptacle. The sides and upper end of the receptacle are connected with the corresponding sides and end of the chute by means of canvas that permits the chute to move relative to the receptacle. Means is provided for vibrating the chute and for depositing sand on its upper end. The bottom of the chute

is formed of pervious material. Extending transversely of the chute above the bottom are riffles over which the material must flow in its passage downwardly. Means is provided for blowing air into the receptacle and for increasing the air pressure to such an extent that air currents will pass upwardly through the layer of ore.

Having thus briefly described the invention, the same will now be described in detail, and for this purpose reference will be had to the accompanying drawings in which one embodiment of the invention has been illustrated, and in which:

Fig. 1 is a side elevation of an apparatus 65 constructed in accordance with this invention;

Fig. 2 is an end view of the apparatus looking in the direction of arrow 2, Fig. 1;

Fig. 3 is a section taken on line 3—3, Fig. 4; 70

Fig. 4 is a top plan view of the chute;

Fig. 5 is a section taken on line 5—5, 75

Fig. 4.

Fig. 6 is a section taken on line 6—6, Fig. 4; and 80

Fig. 7 is a section taken on line 7—7, Fig. 6.

In the drawings reference numeral 1 represents a supporting surface on which the apparatus rests. The apparatus consists of a frame work comprising two vertical supports 2 that are located at the lower end of the apparatus and two other vertical supports 3 located at the opposite end. The vertical supports 3 extend upwardly a considerable distance and cooperate with similar supports 4 in supporting a rotary screen 5. The several supports 3 and 4 are connected by horizontal members 6 so as to form a rectangular framework. Since the specific construction of this framework is independent of the invention that is claimed herein, it will not be described with any greater particularity than is found to be necessary for the purpose of 85 properly explaining the invention.

The vertical supports 2, 3 and 4 are connected by means of a horizontal steel member 8 and a similar steel member 9 extends upwardly in an inclined direction from mem- 100

ber 2 to support 3. Box-like container 10 is supported by the framework comprising supports 2 and 3. In the embodiments illustrated, this container has been shown as formed from sheet metal and has a bottom 11, sides 12 and ends 13 and 14. The end member 13 is higher than end member 14 and the upper edges of the sides are inclined, all in the manner shown in Fig. 5. One end of the bottom 11 is provided with an outlet pipe 15 through which material can be removed when the receptacle is cleaned. Supported above the open end of the receptacle, is a chute that has been designated in its entirety by reference numeral 16. The chute consists of two parallel side members 17 that are connected at their ends by transverse members 18. A bottom 19 formed from eighty mesh screen extends between the side members 17 along the center line of the latter in the manner shown in Fig. 5. Extending transversely of the chute are riffles 20 to the under side of which the screen is attached. A transverse member 21 is located adjacent the upper end of the chute and the upper end of the screen bottom 19 is attached to this transverse member. An inclined plate 22 extends from member 21 to the upper end member 18 and this is spaced a short distance from the upper surface of member 21 so as to provide openings 23 for the escape of air. Member 21 is also provided with openings 24. Each of the riffles is provided with openings 25 that extend from their lower surface to a point near the top, as shown in Fig. 5. A removable board 26 is provided between the lowermost riffle and the lower end 18, as shown in the drawings. Located between one of the ends of the riffle and one side member 17 is a removable board 27 that can be raised when desired and when this is raised, an opening like that indicated by reference numeral 28 in Fig. 3 is provided. When the chute is to be cleaned, the contents can be swept to the side having the opening 28 and can then be swept downwardly to the opening provided by the removal of board 26. Located beneath the screen 19 is another screen 29 that is preferably made of ninety mesh wire and located a short distance below this is a strip of canvas 30 that is supported on a screen 31 of large mesh. A few riffles 32 are secured transversely of screen 29.

The sides of the screen are provided with brackets 33 or some equivalent means and these are adapted to come in contact with stops 34. These stops are adjustable by means of a screw 35 as seen most clearly in Fig. 6. The stops limit the downward movement of the chute and by adjusting the stops the amount of vibration can be controlled. For the purpose of vibrating the chute, cams 36 have been provided. These cams are secured to shaft 37, one end of which is pro-

vided with a pulley 38 with which a belt 39 cooperates. Directly above each of the cams is a bracket 40 whose under surface has a hardened steel plate 41 with which the cam contacts. The cam can be constructed in the manner shown in Fig. 7, or in some other equivalent way. A box 42 surrounds the cam and contains oil so that the cam surfaces are always properly lubricated. The bracket has downwardly projecting sides 43 that overlap the sides of the box 42 so as to exclude dust and dirt. Although the cam has a definite throw, the actual extent of the vibration can be controlled by the stops 34 as above intimated. 70 75 80

Located at the rear of the receptacle is a blower 44 that is connected with the interior of the receptacle by means of a pipe 45. Secured to the inner sides of the receptacle are two or more deflector plates 46 that serve to direct the air upwardly against the bottom of the chute. Plates 46 are preferably so connected with the receptacle that they can be readily removed when the latter is to be cleaned. The end 14 of the receptacle is provided with a screened opening 47 that is protected by means of a baffle plate 48. This opening permits some of the air to escape and this also provides a current of air from the pipe 45 throughout the entire length of the receptacle. In addition to the fan 44, another fan which has been indicated by reference numeral 49, has been provided. The outlet from this fan has been designated by reference numeral 50 and has at its upper end a wide nozzle 51 that terminates within the upper end of the chute directly beneath the plate 22, as shown in Fig. 5. A pipe 52 extends from this nozzle to the chute 53 that comes from the rotary screen. When blower 49 is in operation, it produces a strong blast of air that is directed downwardly into the space between the screens 19 and 29 and this air serves to produce a strong air current through the ore as it flows downwardly over the screen. 90 95 100 105 110

The power is delivered to the shaft 54 by means of a belt that cooperates with a pulley 55. The fan 44 is driven from this shaft by means of a belt 56 and fan 49 is also driven from this shaft by means of a belt 57. Located above the fans is a shaft 58 that is driven by means of a belt 59 and this shaft has a pulley 60 with which a belt 61 cooperates. Belt 61 transmits power to a pulley 62 that rotates the screens in a manner quite apparent from the drawings. The end of shaft 54 has a bevelled gear 63 that cooperates with a corresponding bevel gear 64 on the end of shaft 65. The other end of shaft 65 has a sprocket wheel 66 that cooperates with a sprocket chain 67 which in turn cooperates with a sprocket wheel 68 on the end of shaft 69. A universal joint 70 connects the end of shaft 69 with shaft 71, and this shaft ex- 115 120 125 130

tends upwardly parallel to the upper edge of one of the sides of the chute, and is journaled in bearings 72. Shaft 71 is provided with a number of eccentrics 73, from which connecting rods 74 extend to the transverse rods 75 that are mounted for reciprocation in bearing 76 on the upper edges of the sides of the chute. Fingers 77 extend downwardly from the rods 75 along the upper edges of the 5 riffles and when shaft 71 is rotated, the rods 75 and fingers will reciprocate, thereby keeping the material on the upper side of the riffles agitated so as to facilitate the settling of the gold particles and the passage of the 10 air through the fan at this point. The sand that overflows the riffles will be subjected to a blast of air coming through the openings 25 and the action of this air will serve to remove dust and light particles. There is, of course, 15 a continuous flow of air upwardly through the screen bottom and this in conjunction with the vibration of the chute and the downward motion of the fan keeps the particles in constant motion, thereby permitting the 20 gold particles to gravitate towards the bottom. The small particles of gold will pass through the screen 19 and be caught on the riffles 32 on the lower screen. If any gold 25 particles pass through screen 29, they will be caught on the canvas. The gold that is present in the sand which this machine is 30 designed to operate on, is so fine that some will even pass through the canvas and this will settle on the bottom of the receptacle. The 35 diagonal plates 46 act as baffles to direct the air upwardly in the manner already pointed out.

With a machine constructed in the manner described, the sand is deposited in the 40 hopper 78 and from this it passes into the rotary screens 5 where it is subjected to a succession of screenings and the finer particles pass downwardly through the chute 53 and are deposited on the upper surface of boards 45 22. The fans are operated in the manner described and simultaneously therewith the chute is vibrated. The sand is distributed quite uniformly over the board 22 and thence passes downwardly along the chute 50 overflowing the riffles, and finally passing out over the lower end 18. During the downward passage, the constant agitation of the sand together with the cleaning action of the air currents, permits 55 the gold to gravitate downwardly, the larger particles being retained on the screen and the particles that pass through this screen, being caught either on the screen 29 or on the canvas, or collected in the receptacle. 60

After the machine has been in operation for the length of time desired, it is stopped and the board 27 removed together with the board 26. The material on screen 19 is then 65 swept into the opening 28 and from thence

downwardly into the receptacle. The chute can be removed if desired for the purpose of cleaning the receptacle, although this can be quite satisfactorily effected through the opening normally closed by board 26. The 70 material removed from the receptacle is passed to a clean-up barrel where it is amalgamated with mercury after which it is separated from the mercury in the usual manner. 75

The machine as described above operates without the use of water and in fact operates best when the material is absolutely dry, and it is therefore especially well adapted for arid countries where there is gold mixed with the sand, but no water available. The machine can be operated by means of an internal combustion engine and as this requires merely that gasoline for fuel be transported, it is evident that by means of this machine, it 80 is possible to conduct mining operations in the driest places which has heretofore been impractical because practically all machines and methods that have heretofore been in use required a large amount of water for 85 successful operations.

This machine as actually constructed can readily be taken apart so that it can be shipped or transported without difficulty on trucks, or even on pack mules and is therefore available for any location. 90

The machine described above and claimed herein is adapted for use with all kinds of powdered ore as well as with dry sand and gravel. The term "ore" or sand is intended to embrace all kinds of dry powdered material containing metal particles, such as ground quartz ore, rotten quartz, sand and gravel and it is not limited to any particular material. 100

Having described the invention what is 105 claimed as new is:

1. An apparatus for separating gold from dry powdered ore, or the like, comprising, in combination, a support formed in part by a box-like receptacle having its upper end open and inclined downwardly towards one end, a chute located above the receptacle and inclined in the same direction as the open end of the receptacle, the lower end of the chute being connected to the lower end of the receptacle by hinges, the sides and the other end of the receptacle being connected to the sides and corresponding end of the chute by means of flexible fabric, the bottom of the chute being formed of pervious material, there being a pervious partition located beneath the bottom and spaced from the latter, a plurality of riffles extending transversely of the chute on the upper surface of the bottom, means for depositing a layer of material on the upper end of the chute, means for imparting to the chute an up and down vibration whereby the material will be agitated and made to move downwardly along the 110 115 120 125 130

chute, means for blowing air into the receptacle whereby the air pressure therein will be increased above atmospheric and a flow of air produced through the pervious bottom of the chute and through the material, and mechanical means for stirring the material above the riffles.

2. An apparatus for separating gold from dry powdered ore, or the like, comprising, in combination, a support formed in part by, a box-like receptacle having its upper end open, a chute located above the receptacle and inclined in the direction of its length, the lower end of the chute being connected to one end of the receptacle, the sides and the other end of the receptacle being connected to the sides and corresponding end of the chute by means of flexible fabric, the bottom of the chute being formed of pervious material there being a pervious partition located beneath the bottom and spaced from the latter, a plurality of riffles extending transversely of the chute on the upper surface of the bottom, means for depositing a layer of material on the upper end of the chute, means for imparting to the chute an up and down vibration whereby the material will be agitated and made to move downwardly along the chute, means for blowing air into the receptacle whereby the air pressure therein will be increased above atmospheric, whereby a flow of air is produced through the pervious bottom of the chute and through the material, mechanical means for stirring the material above the riffles, and a separate blower for directing a stream of air into the space between the bottom and the partition.

3. An apparatus for separating gold from dry sand, or the like, comprising, in combination, a support formed in part by, a box-like receptacle having its upper end open, a chute located above the receptacle and inclined in the direction of its length, the lower end of the chute being connected to one end of the receptacle, the sides and the other end of the receptacle being connected to the sides and corresponding end of the chute by means of flexible material, the bottom of the chute being formed of pervious material, there being a pervious partition located beneath the

bottom and spaced from the latter, a plurality of riffles extending transversely of the chute on the upper surface of the bottom, means for depositing a layer of material on the upper end of the chute, means for imparting to the chute an up and down vibration whereby the material will be agitated and made to move downwardly along the chute, means for blowing air into the receptacle whereby the air pressure therein will be increased above atmospheric, a flow of air produced through the pervious bottom of the chute and through the material, the riffles having openings extending from the bottoms to a point on the lower side a short distance below the top, and mechanical means for stirring the material above the riffles.

4. An apparatus for separating gold from dry powdered ore, or the like, comprising, in combination, a support formed in part by, a box-like receptacle having its upper end open, a chute located above the receptacle and inclined in the direction of its length, the lower end of the chute being connected to one end of the receptacle, the sides and the other end of the receptacle being connected to the sides and corresponding end of the chute by means of flexible fabric, the bottom of the chute being formed of pervious material there being a pervious partition located beneath the bottom and spaced from the latter, a plurality of riffles extending transversely of the chute on the upper surface of the bottom, means for depositing a layer of material on the upper end of the chute, means for imparting to the chute an up and down vibration whereby the material will be agitated and made to move downwardly along the chute, means for blowing air into the receptacle whereby the air pressure therein will be increased above atmospheric, a flow of air produced through the pervious bottom of the chute and through the material, the riffles having openings extending from the bottoms to a point on the lower side a short distance below the top, and mechanical means for stirring the material above the riffles.

ISAAC C. LIGHTFOOT.
